AUTOMATIC FIRE DETECTOR, ALARM, AND EXTINGUISHER

Joseph Grison, Braintree, Mass., assignor of seven-eighths to Paul Joseph Ansel, three-eighths to Myrtle E. Ansel, one-twentieth to Frances J. Barnum and Charles A. Dolbier, one-fortieth to J. Joseph Logan, one-twentieth to Harriette B. Logan, one one-hundredth to Leo R. Andrus, three-fortieths to Cecil C. Wright and Cecil W. Wright, and one-fortieth to Ruth K. Goetsche, all of New York, N. Y.

Application October 21, 1935, Serial No. 45,863
Renewed November 23, 1938

4 Claims. (Cl. 169—26)

This invention relates to new and useful improvements in an automatic fire detector, alarm and extinguisher.

The invention has for an object the construction of a device as mentioned which is small, compact, efficient, and which may be operated at a very low cost.

A further object of the invention is a construction whereby the device may instantly detect a fire and automatically send out an alarm and thereafter extinguish the fire. Furthermore, it is proposed to so construct the device that it may be easily installed and safely operated anywhere in the city or country.

15 A still further object of the invention is the construction of a device as mentioned which is not dependent upon any electric lighting circuits that may be put out of commission by a short circuit or fire, and which is not dependent upon batteries or dry cells or chemicals that deteriorate rapidly or require replacement. The invention proposes a construction that remains on the job 24 hours a day, year in and year out, without any servicing.

25 Still further the invention contemplates a construction wherein the heat of a fire reaching the device and attaining a temperature of 145° causes a first sending out of a fire alarm, and thereafter quickly repeating the alarm when the temperature reaches 155° and finally, when the temperature reaches 165° causing the shattering of a glass grenade containing fire extinguishing fluid.

The invention further proposes the provision of fuse elements adapted to fuse at the temperatures specified in the previous paragraph and controlling the operation of powerful coiled spring operating mechanisms which discharge blank cartridges to give the first two alarms mentioned, and finally operating mechanism which breaks 40 the grenade.

Furthermore, it is proposed to so design the device that carbon tetrachloride may be used in the grenade as the fire extinguishing fluid. This ingredient changes into gas almost instantaneously upon contact with heat and greatly expands into a powerful fire smothering blanket which is drawn to the heart of the fire by the draft. It is generally known that a fire creates a natural circulation, or draft, which tends to keep it alive, 45 and it is this draft which is depended upon to draw the extinguishing gas to the central point of the conflagration. The advantage in using carbon tetrachloride resides in the fact that this liquid is harmless; it does not spot or stain the 50 finest fabrics, furniture or equipment. It is ideal

for electrical or motor fires as it is a non-conductor of electricity. It is considered the very best extinguisher for gasoline and oil fires.

For further comprehension of the invention and of the objects and advantages thereof, reference 5 will be had to the following description and accompanying drawing, and to the appended claims in which the various novel features of the invention are more particularly set forth.

In the accompanying drawing forming a material part of this disclosure:—

Fig. 1 is a side elevational view of a device constructed according to this invention.

Fig. 2 is a front elevational view of Fig. 1.

Fig. 3 is a sectional view taken on the line 3—3 15 of Fig. 2.

Fig. 4 is a sectional view taken on the line 4—4 of Fig. 1.

Fig. 5 is a bottom view of a device constructed according to a modification of this invention. 20

Fig. 6 is a fragmentary front elevational view of the device shown in Fig. 5.

The automatic fire detector alarm and extinguisher, according to this invention, comprises a hollow body 10 adapted to be attached on a wall 25 or the like and having open top and bottom ends 10^a and 10^b respectively. A removable top cover 11 closes the open top end 10^a. A lug 12 extends across a portion of the open bottom 10^b leaving a space between its edges and the sides of the hollow 30 body. A breakable grenade 13 of carbon tetrachloride is housed within the hollow body and at its lower end is formed with a neck portion 13^a which is rested upon the shoulder of an opening 12^a formed in the lug 12. The grenade is of a 35 diameter so as to be supported by the side walls of the hollow body.

Several spring operated clappers 15^a, 15^b and 15^c carrying explosive cartridges 16 are mounted on the outer sides of said body 10. Fuse links 40 17^a, 17^b and 17^c of different fusing temperatures hold these clappers, respectively, from exploding their cartridges. The body 10 is formed with an opening 18 through which one clapper, the clapper 45 which is held by the fuse having the highest fusing temperature, may engage and strike the grenade for breaking it.

Each of the clappers is mounted upon a bracket 19 which is attached on the side of the hollow body. These brackets have lugs 20 between 50 which there is a spindle 21. A heavy and strong spring 22 has end portions coaxially mounted upon the spindle 21 and the extremities 22^a of these end portions engage over the lugs 20. The central portions 22^b of each of the springs engage 55

over the top side of the clappers for urging the clappers downward. The clappers are fixed upon the spindles 21 which are rotative in the lugs 20.

The fuse elements are engaged between the clappers and hooks 23 mounted upon the sides of the body. At the lower ends the fuse elements engage upon hooks 24 upon the backs of the clappers by which they connect with the clappers. The construction is such that the fuse elements may be lifted free from the hooks for removal, inspection, and replacement whenever desired.

The cartridges 16 are disposed within bushings 26 which are threadedly engaged into cup shaped elements 27 having depressible discharge pins 28 on their outer ends. The bushings 26 threadedly engage the cup shaped members 27 and clamp edges of the clappers therebetween; a construction by which the cartridges are supported on the clappers. The depressible pins 28 have internal 20 spear shaped heads 28^a adapted to strike the backs of the cartridges to cause their explosion. The outer ends of the pins 28 are formed with slightly flattened portions 28^b to prevent their complete displacement from the cup shaped 25 members 27.

The body 10 has top and bottom flanges 30 with apertures 31 for nails or screws by which they may be attached on a wall or other object. The cover 11 is provided with an internal flange 32 engaging one of the sides of the body by which it is frictionally mounted upon the body.

In the form of the invention illustrated in Figs. 5 and 6, means is provided for holding the clapper which is capable of breaking the grenade 35 from moving until the other clappers have been "shot". This means consists of fingers 33 fixedly mounted at one of their ends upon the spin-dles 21 of the clappers upon the sides of the body 10. These fingers extend around to the front and 40 extend upwards and terminate in end portions 33' engaging beneath the cup shaped member 27 of the front clapper. Thus, should the fuse element of said latter-mentioned clapper break accidentally or for some other reason tend to "shoot" off, it will be restrained by the fingers.

When the side clappers "shoot" off, the end portions 33' will slightly lift the clapper 15^b until they are free. Thus, the side clappers 15^a and 15^c are not restrained from operating. The springs of the side clappers are capable of overcoming the downward urge of the spring from the front clapper 15^b so that the slight lifting of the front clapper is possible.

The operation of the device is as follows:
55 Assume that there is a fire in the vicinity of the device. The heat from the fire will heat the fuse elements until the fuse element 17^a reaches a pre-determined temperature (for example 145°). This temperature is sufficient to cause the fuse
60 element to melt.

Instantly, the clapper 15^a is released and the spring 22 thereof will swing it around so that the firing pin 28 strikes the side of the body 10. This causes the firing pin to be forced inwards 65 striking the cartridge 15 which explodes and gives an audible alarm. The cartridge may be of a conventional known design used for similar purposes and capable of making an extra loud noise.

When the temperature in the vicinity of the device reaches 155° the fuse 11^c blows and the clapper 15^c operates to discharge its cartridge, giving the second alarm. When the temperature reaches 165° the clapper 15^b operates. The head of this clapper strikes through the opening 18 and breaks 75 the grenade. The liquid carbon tetrachloride is

immediately discharged to the floor or ground where it turns into gas. A further feature of the invention is that the cover 11 may easily be moved from the body and the grenade removed and thrown at the center of a fire remote therefrom. 5

While I have illustrated and described the preferred embodiment of my invention, it is to be understood that I do not limit myself to the precise construction herein disclosed and the right is reserved to all changes and modifications coming within the scope of the invention as defined in the appended claims. 10

Having thus described my invention, what I claim as new, and desire to secure by United States Letters Patent is:—

1. In a device of the class described, a hollow body adapted to be attached upon a wall or the like and having an open top end and an open bottom end, a removable cover closing said top end, 20 a lug extending across the bottom of said body leaving a space between its edges and the sides of said body, a breakable grenade of carbon tetrachloride resting on said lug, said body having an opening exposing a portion of the grenade, 25 several spring operated clappers with explosive cartridges mounted on the outer side of said body, fuse links of different fusing temperatures holding said clappers from exploding said cartridges, said clappers being so mounted that when 30 they are released the exploding cartridges carried thereby will strike the outer wall of the hollow body, and the clapper held by the fuse link having the highest fusing temperature being so mounted that when released it will pass through 35 the opening in said body to strike and break said grenade.

2. In a device of the class described, a hollow body adapted to be attached upon a wall or the like and having an open top end and an open bottom end, a removable cover closing said top end, a lug extending across the bottom of said body, leaving a space between its edges and the sides of said body, a breakable grenade of carbon tetrachloride resting on said lug, said body having an opening exposing a portion of the grenade, several spring operated clappers with explosive cartridges mounted on the outer side of said body, fuse links of different fusing temperatures holding said clappers from exploding said cartridges, said clappers being so mounted that when they are released the exploding cartridges carried thereby will strike the outer wall of the hollow body, the clapper held by the fuse link having the highest fusing temperature being so mounted that when released it will pass through the opening in said body to strike and break said grenade, and means for holding the latter-mentioned clapper from moving until the other clappers have been "shot".

3. In a device of the class described, a hollow body adapted to be attached upon a wall or the like and having an open top end and an open bottom end, a removable cover closing said top end, a lug extending across the bottom of said body leaving a space between its edges and the sides of said body, a breakable grenade of carbon tetrachloride resting on said lug, said body having an opening exposing a portion of the grenade, several spring operated clappers with explosive cartridges mounted on the outer side of said body, fuse links of different fusing temperatures holding said clappers from exploding said cartridges, said clappers being so mounted that when they are released the exploding car- 75

tridges carried thereby will strike the outer wall of the hollow body, the clapper held by the fuse link having the highest fusing temperature being so mounted that when released it will pass 5 through the opening in said body to strike and break said grenade, and means for holding the latter-mentioned clapper from moving until the other clappers have been "shot", comprising fingers mounted upon the ends of spindles connected with said other clappers to rotate when the clappers are discharged, and said fingers engaging beneath the said latter-mentioned clapper.

4. In a device of the class described, a hollow body adapted to be attached upon a wall or the like and having an open top end and an open bottom end, a removable cover closing said top end, a lug extending across the bottom of said body leaving a space between its edges and the 10 sides of said body, a breakable grenade of carbon tetrachloride resting on said lug, said body having an opening exposing a portion of the grenade, several spring operated clappers with

explosive cartridges mounted on the outer side of said body, fuse links of different fusing temperatures holding said clappers from exploding said cartridges, said clappers being so mounted that when they are released the exploding cartridges carried thereby will strike the outer wall of the hollow body, the clapper held by the fuse link having the highest fusing temperature being so mounted that when released it will pass through the opening in said body to strike and break said grenade, and means for holding the latter-mentioned clapper from moving until the other clappers have been "shot", comprising fingers mounted upon the ends of spindles connected with said other clappers to rotate when the clappers are discharged, and said fingers engaging beneath the said latter-mentioned clapper, said latter-mentioned clapper being adapted to move up slightly when the other mentioned clappers operate so that the restraining fingers 15 are moved out from their restraining positions. 20
